UNITED STATES PATENT OFFICE.

OSCAR BLOMBERG, OF MUSKEGON, MICHIGAN.

VALVE-SPRING RETAINER.

972,434.

Specification of Letters Patent. Patented Oct. 11, 1910.

Application filed April 29, 1910. Serial No. 558,424.

To all whom it may concern:

Be it known that I, OSCAR BLOMBERG, a citizen of the United States, residing at Muskegon, in the county of Muskegon and State of Michigan, have invented certain new and useful Improvements in Valve-Spring Retainers; and I do hereby declare the following to be a full, clear, and exact description of the invention, such as will enable others skilled in the art to which it appertains to make and use the same.

My invention has for its especial object to provide an improved valve spring retainer or device for securely but detachably holding a spring cap to the valve stem or rod; and to this end, the invention consists of the novel devices and combinations of devices hereinafter described and defined in the claim.

20 In the accompanying drawings, which illustrate the invention, like characters indicate like parts throughout the several views.

Referring to the drawings: Figure 1 is a view chiefly in vertical section, showing portions of the spring and valve stem or rod and illustrating my invention applied thereto, some parts being broken away and some parts being shown in full; Fig. 2 is a transverse section taken on the line $x^2 x^2$ of Fig. 1; Fig. 3 is a transverse section taken approximately on the line $x^3 x^3$ of Fig. 1; and Fig. 4 is a detailed view, showing one end of the valve stem or rod.

35 The valve stem is indicated by the numeral 1 and the spring by the numeral 2. As a means for causing the spring to react against the valve stem, it has been customary to provide a so-called spring cap for engagement with one end of the spring and 40 to secure this spring cap to the valve stem.

45 My invention provides an extremely simple and highly efficient device for detachably locking or anchoring the spring cap to the valve stem and for permitting quick detachment thereof from the stem whenever desired. The spring cap 3 has an axial perforation, adapting it to be slipped freely over the valve stem and it is preferably provided with a marginal flange or laterally 50 turned edge, forming a concave seat, within which the end of the spring is adapted to fit.

55 At the proper point to give the desired

compression of the stem, the valve stem is provided with a notch preferably in the form of an angular groove 4. A retainer or 55 lock plate 5, preferably of oblong form, is formed with an elongated slot, one extremity 6 of which is of sufficient diameter to permit the said retainer to be slipped over and on to the valve stem. The other extremity or portions 7 of the said slot is of such width that it cannot be passed on to the full diameter of the valve stem, but may be slid into interlocking engagement with the lock groove 4. At that end which is 60 adjacent to the large end 6, the retainer 5 is provided with a laterally bent or extended lock lug or flange 8, which when the retainer and spring cap are in working position, as shown in Fig. 1, engages the rim of said cap 70 so that the cap serves in turn to hold the retainer in working position.

When it is desired to remove the spring cap from the valve stem or to move the same on the valve stem so as to relieve the spring 75 from tension, it is necessary first to force the spring cap far enough away from the retainer to permit the latter to be moved radially inward until the large extremity 6 of its slot is brought into registration with the 80 valve stem, whereupon the said retainer may be slipped off of the stem of the said spring cap and the said spring cap will then be free for movement, also, off from the valve stem.

The device above described, while 85 extremely simple and of small cost, has in practice been found highly practical for the purposes had in view. By use thereof, it is made an easy matter to apply springs to valve stems or rods and to remove said 90 springs therefrom. The device is, however, capable of general use, wherever it is desirable to lock a spring cap or similar member of a stem or rod. Attention is, also, called to the fact that the construction of the 95 spring cap and of the retainer are such that both may be stamped from pieces of sheet metal and neither requires boring.

What I claim is:

The combination with a rod having a lock 100 notch, of a spring pressed cap having a perforation adapting it to be positioned on said rod adjacent to said notch, a cap retainer having an elongated slot with rela-

tively wide and narrow extremities, the large extremity of said slot adapting said retainer to be positioned on said rod and the said narrow extremity adapting it for interlocking engagement with the notch of said rod, and a spring normally pressing said press cap against said retainer, and the said retainer and cap having normally engaging

parts, which hold the said retainer interlocked to said rod, substantially as described. 10

In testimony whereof I affix my signature in presence of two witnesses.

OSCAR BLOMBERG.
